United States Patent Office

Des. 220,482
Patented Apr. 20, 1971

220,482

KNEELER

Kurt E. Landberg, St. Louis, Mo., assignor to Burks & Landberg, Architects, St. Louis, Mo.

Filed Sept. 11, 1969, Ser. No. 19,109

Term of patent 14 years

Int. Cl. D6—01

U.S. Cl. D15—8

FIG. 1

FIG. 2

FIG. 4

FIG. 3

FIG. 5

FIG. 6

FIG. 7

FIG. 1 is a top plan view of a kneeler showing my new design.

FIG. 2 is a side elevational view taken from the right hand side of FIG. 1.

FIG. 3 is a side elevational view taken from the left hand side of FIG. 1.

FIG. 4 is a bottom view thereof.

FIG. 5 is a rear view thereof.

FIG. 6 is a front view thereof.

FIG. 7 is a perspective view thereof.

I claim:

The ornamental design for a kneeler, as shown.
